UNITED STATES PATENT OFFICE.

ELI THAYER, OF WORCESTER, MASSACHUSETTS.

STEAM-PUMP.

SPECIFICATION forming part of Letters Patent No. 274,154, dated March 20, 1883.

Application filed March 18, 1882. (No model.)

To all whom it may concern:

Be it known that I, ELI THAYER, of the city and county of Worcester, and State of Massachusetts, have invented an Improvement 5 in Steam-Pumps, of which the following is a specification.

My invention has reference to steam-pumps in general; and it consists in certain improvements therein, all of which are fully set forth 10 in the following specification and shown in the accompanying drawings, which form part thereof.

The object of this invention is to simplify 15 the construction of steam-pumps, and thereby cheapen their manufacture; further, to provide a settling-chamber in which sediment may settle and be blown off; further, to employ two double valves, one of which is the induction and the other the eduction valve; further, to provide 20 a water-cylinder on each side of the settling-chamber, said cylinder being exposed internally, and without heads; further, to so construct the valves that they are closed or opened by the combined action of suction or pressure 25 developed in the two cylinders, as more clearly specified hereinafter.

In the drawings, Figure 1 is an elevation of 30 my improved steam-pump, with the pump proper in section. Fig. 2 is a sectional elevation of my improved induction-valve.

The casting A is provided with the receiving and settling chamber F, into which the water is fed by the induction or feed pipe G. Any dirt or other heavy deleterious substance 35 settles and runs into the chamber f, from which it may be blown by valved outlet f'. This chamber F opens directly into the adjacent ends of the pump or water cylinders B, the said openings being provided with valve-seats, against which the faces h h' of the double 40 induction-valve H seat themselves, alternately closing the aperture to one cylinder and opening the aperture to the other. This valve H is made as follows: One of the faces, h, is provided with a hub, h², and wings H', and the other face, h', fits against the said hub h² and wings H', and is firmly secured in place by a bolt, h⁴, and through the hub h² and bolt h⁴ the piston-rod C works, and is packed by stuffing-box h³ 45 to prevent water passing from one side of the

valve to the other. In practice this packing-box h³ should be on the end farthest from the steam-cylinder, to more easily repack it when necessary.

Rigidly secured to the piston-rod C are the 55 two pistons D—one in each cylinder B—and which pistons may be of the most simple construction, as shown, in which leather packing is used. The upper part of casting A is provided with eduction-valve chamber I, in which 60 the eduction-valve J works to close and open the apparatus, connecting the chamber I with the cylinders B by the ports d. This valve J consists of faces j and j', bolted together by bolt j², said valve-faces seating themselves 65 outwardly and in an opposite direction to valve H. This valve J may be inspected, &c., through hand-holes closed by caps i. The chamber I may be also a settling-chamber, and the impurity blown off by opening i'. 70

K is the air-chamber, and opens into the chamber I.

L is the eduction main or discharge.

As the pistons D move in the direction indicated by the arrow the water from chamber F presses upon the inner side of valve-face h, there being suction on the other side, and the water in end cylinder, B, presses upon the outer side of face h' of the valve H, moving it, as shown. Water is then forced from the end 80 cylinder through the valve J, as shown, into the chamber I and pipe L. When the piston-rod moves in the other direction the reverse operation takes place.

Having now described my invention, what I 85 claim as new, and desire to secure by Letters Patent, is—

1. In a steam-pump, a central casting provided with a support, and in which the valves are located, having on each side an open cylinder, said cylinders being in line with one another, the induction-chamber in said central casting occupying the entire space between said cylinders, substantially as and for the purpose specified. 90

2. The central part, A, provided with water-induction chamber F, into which the supply-pipe G opens, in combination with two water-cylinders, located one on each side of said part A and in line with each other, and 100

- an induction-valve which alternately admits [J, located therein, and adapted to alternately 26
water from said chamber F to each of said
water-cylinders.
3. In a steam-pump, the central part, A, hav-
5 ing induction-chamber F, ports d, eduction-
chamber I, piston-rod C, pistons D D, water-
cylinders B B, located on opposite sides of
said piece A, double induction-valve H, and
double eduction-valve J.
- 10 4. In a steam-pump, the central induction-
chamber, F, provided at the bottom with set-
tling-chamber f, furnished with blow-off f'.
5. In a steam-pump, the combination of part
A, having induction-chamber F and settling-
15 chamber f, cylinders B B, piston-rod C, ex-
tending through part A, pistons D D, induction-
valve H, surrounding said piston-rod C,
and adapted to admit water alternately to each
cylinder, ports d d, chamber I, eduction-valve
- J, located therein, and adapted to alternately 26
open ports d d, with chamber I and steam-
cylinder E.
6. The induction - valve, which consists of
the two oppositely-arranged valve-faces h h',
connected together by a hub or its equivalent, 25
in combination with piston-rod C and packing-
box h³.
7. The induction-valve H, which consists of
the valve-face h, cast solid with hub h², and
wings H', in combination with the valve-face 30
h', screw or bolt h⁴, piston-rod C, and packing
or stuffing box h⁵.

In testimony of which invention I hereunto
set my hand.

ELI THAYER.
